UNITED STATES PATENT OFFICE.

THEODOR EMIL MAXIMILIAN BÜLOW, OF HAMBURG, GERMANY.

WASHING-DOUCHE AND BATH CONTRIVANCE.

SPECIFICATION forming part of Letters Patent No. 513,173, dated January 23, 1894.

Application filed February 27, 1893. Serial No. 463,918. (No model.)

To all whom it may concern:

Be it known that I, THEODOR EMIL MAXIMILIAN BÜLOW, of 37 Neuer Wall, Hamburg, in the Empire of Germany, have invented a new and Improved Combination Washing-Douche and Bath Contrivance, of which the following is a specification, reference being had therein to the accompanying drawings.

This invention relates to bath closets, or the like which, by reason of their triangular square or round form in plan, require only a small space for erection and, by means of the fixing of a lighting shaft thereto, may be also adapted for placing in dark rooms.

5 The drawings hereto annexed represent a closet of triangular form.

Figure 1 is a front view of the closet—closed. Fig. 2 is a perspective view of the same, and Fig. 3 is a vertical transverse section.

20 The door *a b c d* hangs upon the hinges *e f* and has a second door *g h i k* turning upon the horizontal hinges *m n* and fastened in such manner with strips of flexible water-tight material to the door *a b c d* that the 25 turning of the former to a small angle with the door *a b c d* is permitted (as in Fig. 3) and thus light can be admitted to the interior of the closet. The latter serves at the same time

30 to shut in the person bathing from the outside and affords a protection against drafts, &c.—while the opening formed by *g h i k* as shown in Fig. 2 admits light without permitting any escape of water from the interior.

35 Upon the inside of the door *g h i k*, a flap

seat as shown in dotted lines in Fig. 2 may be provided for use when a foot bath is to be taken.

Upon the side wall, a flap *l* is mounted, so as to turn upon horizontal hinges. This flap 40 can be let down and lodges upon a ledge *o* fastened to the opposite wall. (See Figs. 2 and 3.) This serves for the reception of the requisite toilet basin *r* and is turned upon said hinges so as to lie vertically up against the 45 side wall and is there held by a catch when out of use. If this bath closet is in a dark room, a lamp is placed at a suitable distance from the lighting door *g h i k* and the interior of the closet is thus lighted. 50

What I claim, and desire to secure by Letters Patent, is—

A combination washing douche and bathing closet or contrivance consisting of an inclosing chamber of any suitable shape, a main 55 door to gain access thereto, a hinged flap within said closet or contrivance, a subsidiary door hinged to or mounted on said main door and adapted to turn on its lower edge and to open outward at its top edge and provided 60 with suitable water-tight material down each vertical side, and a flap seat secured to said subsidiary door, all substantially as shown and described.

In witness whereof I have hereunto set my 65 hand in presence of two witnesses.

THEODOR EMIL MAXIMILIAN BÜLOW.

Witnesses:

PAUL FISCHER,

PAUL BRINKMANN.
